CEILING LIGHT FIXTURE

Frederick C. Baker, Portland, Oreg.

Application March 8, 1951, Serial No. 14,434

Term of patent 14 years

(Cl. D48—23)

To all whom it may concern:

Be it known that I, Frederick C. Baker, a citizen of the United States, and a resident of Portland, county of Multnomah, and State of Oregon, have invented a new, original, and ornamental Design for Ceiling Light Fixture, of which the following is a specification, reference being made to the accompanying drawings, forming a part thereof, this application being a continuation-in-part of my application for design patent, Serial No. D. 9,425 filed April 22, 1950, now abandoned.

In the accompanying drawings:

Fig. 1 is a bottom perspective view of a ceiling light fixture showing my new design;

Fig. 2 is a bottom plan view thereof;

Fig. 3 is a cross sectional view taken on the line 3—3 of Fig. 2 and looking in the direction indicated by the arrows; and

Fig. 4 is a side elevational view.

I claim:

The ornamental design for a ceiling light fixture, substantially as shown.

FREDERICK C. BAKER.
